UNITED STATES PATENT OFFICE.

WYATT F. PALMER, OF COMANCHE, OKLAHOMA.

COTTON-CLEANER.

1,064,989.

Specification of Letters Patent. Patented June 17, 1913.

Application filed May 8, 1912. Serial No. 696,007.

To all whom it may concern:

Be it known that I, WYATT F. PALMER, a citizen of the United States, residing at Comanche, in the county of Stephens and 5 State of Oklahoma, have invented certain new and useful Improvements in Cotton-Cleaners, of which the following is a specification, reference being had therein to the accompanying drawing.

10 This invention relates to cotton cleaning devices and has special reference to a device for removing the dust, sand and trash from ginned cotton.

The principal object of the invention is to 15 improve and simplify the general construction of devices of this character.

With the above and other objects in view, the invention consists in general of certain novel constructions, combinations and arrangements of parts as will be hereinafter 20 fully described, illustrated in the accompanying drawings, and specifically claimed.

In the accompanying drawings, like characters of reference indicate like parts in the 25 several views, and Figure 1 is a section through a lint flue constructed in accordance with this invention. Fig. 2 is an enlarged detail of a modified form of flue. Fig. 3 is a section on the line 3—3, Fig. 1, on an enlarged scale.

The lint flue constructed in accordance with this invention is made up of a series of galvanized pipe sections 10 connected together after the manner of stove pipes by 30 joints 11 and within these sections are spaced supporting rings 12 which serve to support a screen which is made of screen wire as indicated at 14 or of perforated metal as indicated at 15 in Fig. 2. These sections are 35 arranged beneath or to the back of the gins

used in ginning the cotton, and a current of air is blown therethrough in the direction of the arrow in Fig. 1. Each section communicates with a gin by means of a flue 16 leading through the casing and opening into the 45 interior of the cylindrical screen. It will be noted that this flue 16 is diagonally disposed so that material which is blown through the flue by an air current passing therethrough will sweep around the inside 50 of the screen as indicated by the arrows in Fig. 3. The result of this is that the lint is caused to pass out of the flue in a spiral path and the centrifugal force developed throws all the dirt, sand and trash onto and through 55 the screen so that it drops down into the bottom of the flue from whence it may be removed through a suitable opening 17 closed by a tight fitting door 18.

There has thus been provided a simple and 60 efficient device of the kind described and for the purpose specified.

Having thus described the invention, what is claimed as new, is:—

In a cotton cleaner a cylindrical lint flue 65 made in sections joined together after the manner of stove pipes, spaced supporting rings within said flue, the cylindrical screen supported on said rings and having its walls in spaced relation to said lint flue, a clean out 70 opening in the lower side of said lint flue, a closure for said opening and a flue leading diagonally through said lint flue into said screen as described.

In testimony whereof I hereunto affix my 75 signature in presence of two witnesses.

WYATT F. PALMER.
